CLAIM

The ornamental design for a wireless stereo headset, as shown and described.

DESCRIPTION

FIG. 1 is a perspective view of a wireless stereo headset according to our novel design;

FIG. 2 is a second perspective view of a wireless stereo headset according to our novel design;

FIG. 3 is a top view thereof;

FIG. 4 is an end elevational view thereof, taken from the left of FIG. 3;

FIG. 5 is a right side elevational view thereof;

FIG. 6 is an end elevational view thereof, taken from the right of FIG. 3;

FIG. 7 is a bottom elevational view thereof taken from the opposite side of FIG. 3; and,

FIG. 8 is a left side elevational view thereof, taken from the opposite side of FIG. 5.

The broken lines are for illustrative purposes only and form no part of the claimed design.
